(57) **CLAIM**

The ornamental design for an HVAC control device with animated graphical user interface, as shown and described.

DESCRIPTION

FIG. 1 is a front view of an HVAC control device or portion thereof with graphical user interface showing a first image in an animated sequence of graphical user interface images showing our new design according to a first exemplary embodiment.

FIG. 2 is a front view of the HVAC control device or portion thereof with graphical user interface showing a second image in the animated sequence of graphical user interface images showing our new design according to the first exemplary embodiment.

FIG. 3 is a front view of an HVAC control device or portion thereof with graphical user interface showing a first image in an animated sequence of graphical user interface images showing our new design according to a second exemplary embodiment.

FIG. 4 is a front view of the HVAC control device or portion thereof with graphical user interface showing a second image in the animated sequence of graphical user interface images showing our new design according to the second exemplary embodiment.

The outer perimeter of each image illustrated by broken lines corresponds to an HVAC control device or portion thereof and forms no part of the claimed design. The remaining evenly-spaced broken lines illustrate portions of the graphical user interface that do not form part of the claimed design. The contrast shown in grayscale in the figures represents a contrast of appearance.

The appearance of the transitional image sequentially transitions between the images shown in FIGS. 1 and 2, and FIGS. 3 and 4, though the process or period in which one image transitions to another image forms no part of the claimed design.
